DESIGN FOR A CHILD'S SLEEPING BAG OR SIMILAR ARTICLE

Louis Segerman, Brooklyn, N. Y.

Application March 25, 1941, Serial No. 99,865

Term of patent 14 years

To all whom it may concern:

Be it known that Louis Segerman, a citizen of the United States and resident of the Borough of Brooklyn, in the county of Kings and State of New York, has invented a new, original, and ornamental Design for a Child's Sleeping Bag or Similar Article, of which the following is a specification, reference being had to the accompanying drawing, forming part thereof, in which

Fig. 1 is a front elevation of a child's sleeping bag embodying my new design with the front flap shown partially folded down;

Fig. 2 is a similar front elevation thereof with the said flap shown fully unfolded and the upper portion of the garment shown open; and

Fig. 3 is a rear elevation thereof.

I claim:

The ornamental design for a child's sleeping bag or similar article, substantially as shown and described.

LOUIS SEGGERMAN.
